UNITED STATES PATENT OFFICE.

HARRY F. JORDAN, OF CHICAGO, ILLINOIS, ASSIGNOR OF ONE-HALF TO
ALBERT L. BENTLEY, OF SAME PLACE.

ELECTRIC PROGRAM-CLOCK.

SPECIFICATION forming part of Letters Patent No. 659,479, dated October 9, 1900.

Application filed December 15, 1899. serial No. 740,436. (No model.)

To all whom it may concern:

Be it known that I, HARRY F. JORDAN, a citizen of the United States of America, and a resident of Chicago, in the county of Cook 5 and State of Illinois, have invented certain new and useful Improvements in Electric Program-Clocks, of which the following is a specification.

The main objects of my invention are, first, 10 to provide an electric program-clock of simple construction in which the alarm-plugs may be set for day and night and provided with suitable mechanism to prevent any night alarm from ringing when the corresponding 15 hour of the day is reached, or vice versa; second, to provide improved switch mechanism whereby the different plug-retaining circles will be alternately insulated from the alarm mechanism for the purpose hereinbefore mentioned; third, to provide an improved 20 circuit-closing arm adapted for contact with plugs seated in circles of different radii, and, fourth, to provide an improved form of plug-retaining sockets. I accomplish 25 these objects by the mechanism shown in the accompanying drawings, in which—

Figure 1 is a front elevation of a program-clock constructed according to my invention and having part of the casing and circuit-closing arm broken away to reveal parts within. Fig. 2 is a vertical section of same on the line 2 2 of Fig. 1. Fig. 3 is a rear elevation of the switch. Fig. 4 is the same view of the gear-wheel and switching-disk 35 with the parts shown at the front of Fig. 3 removed. Fig. 5 is a top plan of the parts shown in Fig. 3. Fig. 6 is a section on the line 6 6 of Fig. 4. Fig. 7 is a perspective view of the contact end of the circuit-closing 40 arm. Fig. 8 is a rear view of part of the front wall and showing the interior structure of the different sockets.

The casing 1 has therein a clock-movement 3 and a battery 4 and supports an electric 45 bell 5. The front wall 7 of the casing is provided with an outer circle or ring 8 and an inner circle or ring 9. Each circle consists of a series of sockets 10, connected by wires 11. The outer circle 8 has its wire 11 connected 50 to the wire 12, which passes to the switch. The inner circle 9 is likewise connected to

the wire 13, passing to the switch. The wire 14 connects the switch with the battery. The wire 15 connects the battery with the bell, and the wire 16 connects the bell with the 55 clock mechanism and through same with the circuit-closing arm 17. The circuit-closing arm is supported on the arbor 18 of the hour-hand. The gear-wheel 19, which is rigid on said arbor 18, is driven by the pinion 20 of 60 the clock-movement. Said pinion also drives the gear-wheel 21 of the switch. The gear-wheel 21 is provided with double the number of teeth that are carried by the gear-wheel 19. Thus at each complete revolution of the hour-hand 22 the gear-wheel 21 will make half 65 of a revolution. The gear-wheel 21 is provided with a disk 23, of insulating material, said material being fastened to said gear-wheel by the screws 24, which do not extend 70 entirely through said insulating material. A metallic band 25, of semicircular form, is let into said insulating material, flush with its face on one side of said disk. A similar semicircular band 26, of smaller radius, is let 75 into the face of said disk on the opposite half. Said disks are connected to the insulating material by pegs 27, which do not extend through to the wall 21. The plate 28 has thereon the insulating-blocks 29 and 30. The 80 block 29 supports the wire 14, which connects with a spring contact-point 31, which is connected to the block 29 by the screw 32. The block 30 has the spring contact-points 33 and 34 connected thereto by the screws 35 and 36, 85 respectively. The wire 12 connects with the contact-point 33 and the wire 13 connects with the contact-point 34.

The disk 23 and wheel 21 are journaled in the plate 28 by the shaft 37. The contact 90 end of the circuit-closing arm, as shown in Fig. 7, has a part 38, bent inwardly, so as to pass free from any contact-plugs 39 that may be seated in the inner retaining ring or circle 9. The arms 39 and 40 are pivoted at 95 41 and 42, respectively, to the member 43 of said circuit-closing arm. The spring 44 holds the members 39 and 40 normally in the position shown, with their inner ends abutting the stop 45 on said member 43. Either or 100 both arms 39 and 40 may thus have their free ends moved upwardly from the position shown

in Fig. 7 against the action of the spring 44. Thus when either of said arms comes in contact with a plug in one of the circles 8 or 9 said arm will remain in contact with said plug until the circuit-closing arm has been carried far enough by the clock-movement to permit said arm 39 or 40 to pass the plug and assume its normal position.

The sockets 10 each consist of the metallic eyelet, having its rim slotted to form the projecting ears 46. The wire 11 is given a single turn around each eyelet and proceeds thence to the next. The main part of the flange of the eyelet is bent over in the usual way, while the ears 46 project inward slightly and are designed to insure contact between the eyelet and the plug that may be inserted therein.

Each plug 39' is provided with a memorandum-tablet 47.

48 represents the ordinary clock-dial. A second dial 49 is preferably provided between the circles 8 and 9. The outer circle 8 will preferably be used for all day calls, being those between six o'clock a. m. and six o'clock p. m. The inner circle will in such case be used for the night calls.

The operation of my device is as follows: The operator will set his plugs in the eyelet at the proper time when a call is desired, as denoted by the dial, setting same either in the day or night circle, as may be desired. During the day-time the contact-point 33 will be on the metallic band 25. When the circuit-closing arm now comes in contact with a plug in the outer circle, an electric circuit will be formed through the circle 8, the wire 12, the band 25, contact-point 31, wire 14, battery 4, wire 15, bell 5, wire 16, clock-movement, and circuit-closing arm 17. Thus the alarm will be sounded as long as the member 40 of the circuit-closing arm remains in contact with one of the plugs 39'. During the day-time the contact-point 34 will be on the part 50 of the disk 23, and will thus be insulated from the contact-point 31. Thus if there are any plugs in the inner circle 9 while same will come in contact with the arm 39 of the circuit-closing arm such contact will not establish a complete electrical circuit, since said circuit will be broken at the switch between the contact-points 34 and 31. When the hour-hand has made a complete revolution—say to six o'clock in the evening—then the contact-point 34 will have contact with the metallic band 26 of the switch and will

remain in contact with same during an entire revolution of the hour-hand. During this time, it will be seen, the circuit with the inner circle 9 will be complete through the contact-point 34, band 26, contact-point 31 whenever the circuit-closing arm comes in contact with a plug in said inner circle. During this time also the contact-point 33 will rest upon the insulating material 23 and will thus prevent any circuit being formed through the plugs in the outer circle.

It will be understood that either circle 8 or 9 may be used for day or night, as may be desired, depending upon the position to which the wheel 21 and disk 23 are adjusted when same are connected with the clock mechanism.

It is plain that many details of my device may be altered in numerous ways without departing from the spirit of my invention. I therefore do not confine myself to such details except as hereinafter limited in the claims.

What I claim as my invention, and desire to secure by Letters Patent, is—

1. In an electric program-clock, the circuit-closing arm having a bend 38, and the oppositely-extending arms 39 and 40 pivoted outward of said bend, and secured by means holding same in their normal positions, substantially as described.

2. In an electric program-clock, the combination of a casing; a clock-movement; an electric alarm; a pair of concentric plug-retaining circles on the casing; a circuit-closing arm carried by the clock-movement; the plugs for establishing an electric connection between said circles and arm; and an electric switch operated by the clock-movement, for establishing an electric connection first between one of said circles and said alarm and then between the other of said circles and said alarm, substantially as described.

3. In an electric program-clock, the circuit-closing arm having a bend or recess as at 38, and a pair of oppositely-extending spring-arms secured to said circuit-closing arm outward of said bend or recess, one of same extending partly across said recess, substantially as described.

Signed by me at Chicago, Illinois, this 13th day of December, 1899.

HARRY F. JORDAN.
